UNITED STATES PATENT OFFICE.

LYNWOOD B. JACKSON, OF ASHEVILLE, NORTH CAROLINA.

BOTTLE-TESTER.

1,204,664.

Specification of Letters Patent. Patented Nov. 14, 1916.

Application filed March 9, 1916. Serial No. 83,140.

To all whom it may concern:

Be it known that I, LYNWOOD B. JACKSON, a citizen of the United States, residing at Asheville, in the county of Buncombe and State of North Carolina, have invented 5 certain new and useful Improvements in Bottle-Testers; and I do hereby declare the following to be a full, clear, and exact description of the invention, such as will enable others skilled in the art to which it 10 appertains to make and use the same.

The invention relates to a device for testing bottled beverages.

The object of the present invention is to 15 provide a simple, practical and comparatively inexpensive device adapted to enable bottled beverages to be thoroughly examined and handled with greater rapidity than has heretofore been possible with work of this 20 character and without danger to the operator or liability of injuring his eyesight.

A further object of the invention is to 25 provide a bottle tester of this character adapted to completely expose a plurality of bottles to the action of the light and capable of automatically cutting off the light from the eyes of the operator when the bottles are removed.

Another object of the invention is to 30 agitate the contents of the bottle during the inspection thereof so that the syrup contained in the bottles will be thoroughly mixed with the water so that the condition of the contents may be clearly seen as well as whether 35 the bottles contain any foreign matter.

With these and other objects in view the invention consists in the construction and novel combination and arrangement of parts hereinafter fully described, illustrated in 40 the accompanying drawings and pointed out in the claims hereto appended, it being understood that various changes in the form, proportion and minor details of construction may be resorted to without departing 45 from the spirit or sacrificing any of the advantages of the invention.

In the drawing Figure 1 is a perspective view of a bottle tester constructed in accordance with this invention, Fig. 2 is a 50 vertical transverse sectional view of the same, Fig. 3 is a vertical sectional view taken longitudinally of the bottle tester.

Like numerals of reference designate corresponding parts in the several figures of 55 the drawing.

In the accompanying drawing in which is

illustrated the preferred embodiment of the invention, the bottle tester comprises in its construction a casing composed of a bottom 1, front and rear walls 2 and 3 and side 60 walls or end walls 4.

The bottom is preferably constructed of wood and the walls are made of heavy sheet metal but any other suitable material may of course be employed in the construction 65 of the casing. The front and rear walls 2 and 3 are provided with arcuate upper portions 5 and 6 located at different elevations, the rear arcuate portion being higher than the front arcuate portion. The side or end 70 walls have inclined upper edges 7 which extend forwardly and downwardly to the front arcuate portions 5 from the rear arcuate portion 6 and the said side or end walls also support a horizontal pivot 8 consisting 75 of a rod located at the rear portion of the casing and piercing the said walls 4 and also end flanges 9 of a top 10. The top 10 which is also provided with curved or arcuate front and rear flanges 11 and 12 is 80 adapted to swing downwardly from the elevated position illustrated in Fig. 2 of the drawings to the dotted line position shown in the same figure to arrange a plurality of bottles 13 in an inclined position for 85 causing an agitation of the contents of the bottles and for also exposing the same more completely to the view of the operator whereby the contents of the bottles may be completely inspected. The top 10 which is 90 adapted to swing upwardly and downwardly on the horizontal pivot 8 is provided with a plurality of openings 14 preferably 95 four in number so that the operator using both hands may conveniently place four bottles on the tester and remove the same from the tester simultaneously. The top is normally supported in an elevated position by a coiled spring 15 secured to the rear wall of the casing and to the pivoted top 10 as 100 clearly illustrated in Fig. 2 of the drawing. The spring 15 swings the top upwardly to the elevated position shown in full lines in Fig. 2 of the drawing as soon as the bottles are removed and the light from a 105 lamp 16 is thereby cut off from the eyes of the operator. Also the openings 14 which conform to the configuration of the bottles are entirely covered by the same so that even when inspecting the contents of the 110 bottles, the eyes of the operator are not exposed to the direct glare of the lamp 16.

In practice, the operator will stand in front of the bottle tester which may be conveniently arranged upon a stand, table or other suitable support and the bottles are removed from a case conveniently placed in front of the tester. Four bottles may be tested at each operation of the tester and the contents of the case may be more thoroughly examined in less time than is possible when the bottles are held up two at a time in front of an ordinary electric light which is the method ordinarily resorted to in bottling establishments.

The present invention is designed particularly for inspecting bottles containing soft drinks or non-alcoholic beverages although the tester may be used for analogous purposes. It is customary in filling bottles with non-alcoholic beverages or soft drinks to first place in the bottle an ounce of syrup and then fill the bottle with the carbonated or other water. Any glass or extraneous matter will collect in the syrup and it is necessary to agitate the contents of the bottle in order to properly inspect the same. When the bottles are placed in position upon the top of the tester, the latter swings downwardly to the position illustrated in dotted lines in Fig. 2 of the drawing under the weight of the bottles and the contents of the bottles are automatically agitated so that the bottles may be thoroughly inspected. In the downward swinging of the top the bottles are partially inverted and the pivot is located adjacent to the bottoms of the bottles. Also the pivoting of the top at the side as shown permits a relatively great swing or movement of the top to effect the desired agitation of the contents of the bottles. Should it be desired however, to operate with the top of the tester in a fixed position it may be locked in the dotted line position by means of the pivoted hook or catch 16 secured by a rivet 17 or other suitable fastening device to the rear wall of the casing and adapted to be swung upwardly into engagement with the rear edge of the curved flange 12 to prevent the top from being elevated by the spring 15. The top is preferably provided with a rubber mat 18 having openings 19 conforming to the configuration of the apertures of the top. The mat is preferably provided with a checkered or roughened surface but it may be of any desired construction as will be readily understood.

The lamp 16 is preferably an electric lamp and in order to prevent water from dropping through the casing on to the conducting wires 20, the casing is provided at the top with a transparent plate 21 of glass or other suitable material arranged at an inclination and extending downwardly and forwardly with its front end in flush relation with the upper edge of the front wall

5 to permit the water to drain off exteriorly of the casing. The glass is supported by a flange 22 preferably formed by angle strips secured to the inner faces of the front wall and the side or end walls. The electric 70 lamp is mounted in a socket 23 and the wires 20 extend through an insulating tube 24 which passes through the rear wall of the casing. When it is desired to obtain access to the interior of the casing to change 75 the lamp 16 or clean the same the spring 15 may be drawn forwardly slightly to bow it and enable the top to be swing upwardly beyond the position illustrated in full lines in Fig. 2 of the drawings. This will permit the removal of the glass 21 and will afford access to the interior of the casing.

What is claimed is:

1. A bottle tester including a casing provided with an interiorly arranged lighting device, a pivotally mounted top having openings and adapted to receive a plurality of bottles to enable the same to be exposed to the light, said top being adapted to swing downwardly to an inclined position under 90 the weight of the bottles, agitate the contents of the same and means for automatically lifting the top when the bottles are removed.

2. A bottle tester including a casing provided with an interiorly arranged lighting device, a pivotally mounted top having openings and adapted to receive a plurality of bottles to enable the same to be exposed to the light, said top being adapted to swing downwardly to an inclined position under 100 the weight of the bottles to agitate the contents of the same, a spring connected with the top for automatically lifting the same, and means for locking the top in an inclined 105 position against the action of the spring.

3. A bottle tester including a casing provided with an interiorly arranged lighting device, a pivotally mounted top having openings and adapted to receive a plurality of bottles to enable the same to be exposed to the light, said top being adapted to swing downwardly to an inclined position under 110 the weight of the bottle, a spring connected with the top for automatically lifting the same, and a catch pivotally mounted on the casing at the back thereof and arranged to engage the top for locking the same in an inclined position.

4. A bottle tester including a casing having an interiorly arranged lighting device, a top extending over the casing and pivoted at its rear portion to the same and arranged to swing upwardly and downwardly to arrange it in an inclined position and to elevate it therefrom, said top being provided with a plurality of openings and adapted to expose bottles to the action of the lighting device and agitate the contents of the said bottles and a transparent plate arranged 120

within the casing and interposed between the bottles and the light and arranged to shed water.

5. A bottle tester including a casing provided at the upper portion with opposite curved walls, a top having front, rear and end flanges and fitted over the casing, said top being pivoted at its rear portion to the casing and having its front and rear flanges 10 curved and arranged in spaced relation with the curved walls of the casing, said top being provided with a plurality of bottle receiving openings to enable bottles to be exposed to the light contained within the 15 casing and to cause the bottles to swing downwardly and agitate their contents.
6. A bottle tester including a casing having front and rear walls provided with curved portions arranged at different elevations, the rear wall being higher than the 20 front wall, a supporting flange located within the casing and set at an inclination, a transparent plate arranged upon the supporting flange, a top pivoted to the casing

and having curved front and rear flanges 25 arranged contiguous to the curved portions of the front and rear walls of the casing, said top being provided with bottle receiving openings, whereby the top is caused to swing downwardly under the weight of the 30 bottles to agitate the contents of the latter, and a light mounted within the casing.

7. A bottle tester including a top having a bottle receiving opening conforming to the configuration of the bottle and means 35 for pivotally mounting the top at one end of the opening adjacent to the bottom of the bottle whereby the top is caused to swing downwardly under the weight of the bottle to invert the same and agitate the contents 40 thereof.

In testimony whereof I affix my signature in presence of two witnesses.

LYNWOOD B. JACKSON.
